METHOD FOR CONVERTING HEAVIER OILS INTO LIGHTER OILS

Application filed August 3, 1923. Serial No. 655,448.

This invention relates to an improved method for the conversion of high boiling petroleum hydrocarbons into lower boiling hydrocarbons.

5 In the so-called cracking or destructive distillation of heavier fractions of crude petroleum, by distillation under pressure, the heavier hydrocarbons are broken down and converted to a greater or less extent into 10 lower boiling hydrocarbons. Attempts have been made to operate pressure stills in such a manner that only commercially valuable products will be given off, but with existing methods, certain waste products are always 15 given off during a pressure still run, particularly carbon or coke and non-condensable gases.

Attempts have been made to utilize the non-condensable gases given off by a pressure still, as, for example, by burning them as fuel, but only the fuel value of the gases is utilized in this way. The non-condensable gases, usually amounting to around 2 to 10%, are commonly treated as a refining loss.

25 According to the present invention, these permanent gases are utilized in a particularly advantageous way with material reduction in the refining loss and with increase in the amount of gasoline produced, thus making 30 the pressure distillation a more profitable method of operation.

According to the present invention, substantially all of the so-called permanent gases given off during the operation of the 35 pressure still are absorbed by and admixed with the feed oil charged into the pressure still by charging the feed oil with the gases under pressure, and the feed oil with the gases absorbed and admixed therein is then 40 introduced into the pressure still.

Instead of absorbing the non-condensable gases from the pressure still itself in the feed oil, other hydrocarbon gases can be similarly absorbed in the feed oil under pressure 45 and similarly introduced into the pressure still with the feed oil. Accordingly, in its broader aspects, the invention includes the absorption of other hydrocarbon gases, as well as the gases from the pressure still, in 50 the feed oil, and the introduction of the feed

oil containing the gases absorbed and entrained therein into the pressure still.

It is well known that certain hydrocarbon gases contain not only non-condensable gases but also condensable and liquefiable constituents and attempts have been made to recover these constituents by absorbing them in a hydrocarbon oil from which the condensable constituents are recovered by redistillation, the absorbent oil being then utilized again 55 for the absorption of further amounts of condensable constituents. In such scrubbing or condensing operations the permanent gas passes off practically unabsorbed. According to the present invention, hydrocarbon 60 gases containing such liquefiable constituents, may be absorbed in and admixed with the feed oil along with the non-condensable gases; and the process of the present invention provides an advantageous method of recovering such condensable constituents without the necessity of utilizing a separate absorption and distillation process.

The invention is of particular application in pressure distillation processes which are 75 operated continuously or with continuous introduction of fresh feed oil during the progress of the cracking operation. In such continuous processes, the permanent gases given off during the pressure distillation may, to a greater or less extent, be absorbed in the feed 80 oil and returned therewith to the pressure still. Such condensable constituents of the gases as have escaped condensation in the condenser can advantageously be recovered 85 by returning them to the still along with the feed oil.

Absorption of the gases in the feed oil can be carried out in a substantially continuous manner by forcing the gases under pressure 90 into the feed oil, for example, by passing the oil and gases under pressure into or through an absorber where they are brought into intimate contact and where the pressure will serve to promote absorption and saturation 95 of the oil with the gas.

The entire amount of non-condensable gas from the pressure still may in some cases be absorbed in the feed oil, or a part only of the gases may be so absorbed. It will be evident 100

that the amount of gases given off from a pressure still will vary somewhat with the temperature, pressure, and other conditions of operation, and that the amount of feed oil introduced into the pressure still may similarly vary, depending upon the operation of the still, the amount of tar withdrawn during the cracking operation and like considerations.

- 10 If the amount of cold feed oil is insufficient to absorb all of the gases under the prevailing pressure, the excess unabsorbed gases may advantageously be returned to the still in an unabsorbed state, either in admixture with 15 the feed oil or separately, in which case the advantages incident to the return of the unabsorbed gases will be obtained in addition to those resulting from the return of the gases absorbed or dissolved in the feed oil.
- 20 The feed oil containing the gases absorbed and entrained therein under pressure can be introduced directly into the body of oil in the still or into a reflux tower; and, in the case of a circulating body of oil, they may be introduced 25 into the circulatory stream. One advantageous method of operation is to introduce the feed oil directly into the bottom of the body of hot oil in the pressure still so that both the feed oil and the gases absorbed 30 therein, either with or without additional unabsorbed gases, will be subjected to the high temperature prevailing in the oil into which the feed is introduced. The heating of the feed oil by bringing it into the body of oil 35 heated to the cracking temperature will tend to drive out of solution part or all of the gases absorbed in the feed oil while cold, but this setting free of the gases will assist in distributing the feed oil in the body of the hot 40 oil, and the gases driven out of solution will be brought into intimate contact with the hot body of oil at substantially the point of maximum temperature in the pressure still, so that opportunity for reaction between the 45 gases and the hot oil will be presented. The setting free of the gases from their solution in the feed oil will also serve to agitate the body of oil, and the gases escaping from the body of oil into the vapor space of the still 50 will have a further opportunity of reacting therein.

In the operation of a pressure still, when permanent gas is removed during the distillation, further amounts of permanent gas 55 form, and an equilibrium appears to be continually re-established. By re-introducing substantially all of the gases into the still, the formation of further amounts of permanent 60 gas is prevented or retarded, while the gas which is returned appears to combine to a very considerable extent, with the resulting improvement in the amount of gasoline produced as well as in its quality, and the permanent 65 gases which are withdrawn will tend to

become more saturated, while the tendency to form coke is also retarded.

The manner in which the gases are absorbed in the feed oil, can be varied, as well as the amount of the gases and condensable vapors so absorbed. Where the gases are obtained from some other source than the pressure still itself, for example, where the gases are those given off by a coke still, the gases may be compressed by a suitable pump and forced into the feed oil under a pressure somewhat greater than that maintained in the pressure still. Where the gases are those given off by the pressure still itself, these gases, if collected in a low pressure receiver or gas holder, may similarly be compressed and forced into the feed oil under a pressure somewhat in excess of that in the pressure still.

The invention will be further described in connection with the accompanying drawings illustrating certain preferred embodiments of apparatus adapted for carrying out the process of the invention, but it will be understood that the invention is illustrated by these embodiments and is not limited thereto.

In the accompanying drawings, Fig. 1 shows, in a somewhat schematic and diagrammatic manner, partly in plan and partly in elevation, one arrangement of the apparatus, and Fig. 2 shows, in a similarly schematic and diagrammatic manner, partly in plan and partly in elevation, another arrangement of the apparatus.

Referring first to the apparatus shown in Fig. 1, a pressure still of the shell type is indicated by 1, having a reflux tower 2 thereon, from which the vapors and uncondensed gases escape through the line 3 to the condensing coil 4, the pressure being either reduced by a suitable pressure regulating valve 4^a between the still and the condenser or being controlled by a pressure-reducing valve arranged beyond the condenser. The condensed liquid escapes from the condenser 4 to the receiver 5, while the permanent gas passes to the gas receiver 6, which may have a gas line 6^a leading to a gasometer or a suitable place of gas storage or use. From the gas receiver the gas is pumped to the gas absorption tank 7.

The feed oil, such as gas oil charging stock, is supplied from the tank 8, by means of the oil pump 9 through the line 10 to the gas absorption tank, where the cold feed oil is brought into intimate contact with the high pressure gases. With cold feed stock and with gases introduced at a high pressure, a rapid absorption of a considerable amount of gas takes place, which absorption can be promoted by suitable means for bringing the oil and gas into more intimate contact, for example, by introducing the gas and oil beneath a perforated plate or through injector nozzles and thereby increasing the intimacy 130

of contact of the gas and oil. From the gas absorption tank 7 the oil with absorbed gas, and either with or without excess unabsorbed gas, is forced through the line 11, and enters 5 the still through the line 12, and the perforated feed line 13. By means of such a perforated feed line or spray line, the feed stock is introduced into the bottom of the pressure still so that the oil and gases come 10 in contact with the highly heated oil. The heating of the feed oil will drive the absorbed gases out of solution, more or less rapidly. This escape of gas from the cooler feed oil into the hotter body of oil in the pressure 15 still will promote inter-mixture and agitation of the oil, while the gases themselves will be brought into intimate contact both with the hot liquid oil and with the hot vapors in the pressure still. The gases are thus introduced 20 in a particularly advantageous manner into the heated body of oil and vapors where active cracking is taking place, and opportunity for reaction or re-combination of the gases with the oil and with the 25 vapors is thus provided. Such amounts of the gases as remain dissolved or absorbed in the feed oil will likewise be brought into intimate and reactive relation with the hot oil in the still as the cooler feed oil is intimately 30 mixed therewith, thus providing added opportunity for reaction of the dissolved gases with other constituents in the pressure still. The introduction of the feed and absorbed admixed gases into the hottest portion of 35 the still accordingly provides a most intimate contact of the gases with the unsaturated and reactive constituents in the still.

In the apparatus illustrated diagrammatically in Fig. 1, if the pressure is released by 40 means of a valve 4^a between the still and the condenser, the gas in the gas receiver 6 will be at approximately atmospheric pressure, and the pump will compress this gas and force it into the gas absorption tank 7. 45 Control over this gas absorption and injection is provided by placing valves between the low pressure gas receiving tank 6 and the compressor, and also between the compressor and the gas absorption tank 7; also by providing a by-pass (not shown) from the compressor discharge to the low pressure gas receiving tank, which will permit excess gas to be circulated so that any desired degree of 50 control is provided. Where a part only of the gas is to be absorbed in the feed, the excess gas may escape through the pipe 6^a to a gas receiver or storage tank.

Where all of the gases are not absorbed in the cold feed oil, the excess unabsorbed gas 55 may also be forced into the gas absorption tank and carried along with the feed oil to the pressure still. In this case, the amount of the gases introduced into the still will be greater than that which would be introduced 60 in solution in the feed oil, and such un-

absorbed gases will tend to escape more rapidly through the body of hot oil into the vapor space of the pressure still, although a more or less intimate inter-mixture of the oil and unabsorbed gas may take place in the feed line. Such excess gas will further tend 70 to agitate the oil in the still and to promote the dissemination of the fresh feed throughout the body of hot oil in the still.

In the apparatus illustrated in Fig. 2, I have shown an arrangement adapted for the practice of the invention in connection with a pressure still such as that illustrated in U. S. Letters Patent No. 1,285,200 granted to the Sinclair Refining Company, November 19, 1918 on the application of Edward W. Isom. In the apparatus thus illustrated, the bulk supply tank 16 containing the main body of oil is located away from the furnace and the oil is circulated from this bulk supply tank through the line 17 to the pump 18 and thence through the line 19 to the battery of tubes 20 suitably arranged in the heating flue of the furnace 21. From the upper end of the tubes 20 a line 22 leads back to the bulk supply tank. A reflux tower 23 is arranged above the bulk supply tank 16, being connected therewith by the vapor line 24 and the return oil line 25. The overhead distillate escapes through the pipe 26 to the condenser 27 leading to the receiver 28 for the pressure distillate. The uncondensed gas is collected in the gas receiver 29 and is pumped by the pump 30 to the absorber 31 to which the feed oil is supplied from a suitable 80 supply tank through the line 32.

The feed oil with the gas absorbed therein under pressure, and either with or without excess unabsorbed gases, may be supplied either through the line 33, to the top of the reflux tower, and into the reflux tower at 34, or it can be supplied through the line 35, to the bearings 36 of the pump 18, where it may enter the circulatory stream of oil through the pump bearings. A line for drawing off 90 tar and for initially charging the still is indicated at 37.

In the pressure still illustrated in Fig. 2 the feed oil containing the absorbed gases, and either with or without excess unabsorbed gas, may be introduced either into the reflux tower, or into the circulating oil through the pump bearings, or in part through each of these places. Where the feed is introduced into the top of the reflux tower it will be heated by coming in contact with the hot gases in the tower, and the absorbed gases will be more or less completely driven out of solution and caused to intermix with the hot vapors, thus increasing the content of permanent gases in the reflux tower and diluting the vapors therewith, and providing more or less opportunity for reaction with the vapors.

Where the feed is introduced into the cir- 130

culating line through the pump bearings, the pump will serve to intermix the feed oil and hot circulating oil and will thus bring the feed oil and gases into intimate contact with the hot oil; the resulting mixture will then be forced through the heating tubes where further opportunity will be provided for reaction of the gases with the hot oil, while the gases will also promote the circulation of the oil through the vertical tubes by their air-lift action.

It is well known that a considerable portion of unsaturated hydrocarbons are present both in the permanent gases and in the pressure distillate from pressure stills, as well as in the oil and vapor in the still itself during the cracking operation. While I do not desire to limit myself by any theoretical explanation of the action which takes place when the permanent gases are returned to the still, according to the present invention, yet I believe that reaction takes place between the returned gases, to a greater or less extent, and the hot oil and oil vapors in the pressure still, and particularly between unsaturated constituents of the gases and the oils and vapors, and that this action is promoted by the intimate manner in which the gases are introduced in solution in the feed oil, and particularly where the feed oil and absorbed and entrained gases are introduced into the hottest portion of the still where active reaction is presumably taking place.

The present invention results in an improvement in the quality and an increase in the amount of the gasoline distillate produced, giving a gasoline of a higher degree of saturation which is light in color and easier to refine than ordinary pressure distillate, thus reducing the refining loss, while increasing the amount of the gasoline distillate and facilitating the pressure still operation and control, as well as reducing the amount of permanent gases to be otherwise disposed of, and reducing the tendency toward coke formation.

While I have described and illustrated the invention as applied in the operation of two types of pressure stills, with which it may advantageously be practised, yet it will be understood that the invention is of more or less general application and can be practised in connection with pressure stills of various kinds, both tubular and of the shell type, where more or less continuous feed of fresh oil takes place during the pressure still operation. Where the feed oil with absorbed and entrained gas is introduced into a circulatory system, such as a tubular cracking coil, or system, the gases may assist the circulation while they will be brought into intimate contact with the hot oil while it is being circulated.

It will be evident that the pressure and temperature maintained in the pressure still

can be varied, and that the nature and amount of the charging stock to be fed to the pressure still may also be varied. In pressure stills of the kind illustrated, pressures of around 90 to 125 lbs. (for example) may be used, and the charging stock may be ordinary gas oil such as is used in pressure stills operated at such pressures. Such gas oil will, when cold, rapidly absorb a large amount of the gases and will hold them in a dissolved or absorbed state, until the oil becomes heated upon introducing it into the pressure still. With tubular cracking stills a lighter charging stock can be used, for example, a light gas oil or kerosene charging stock, and the gases may be similarly absorbed in it and introduced therewith into the tubular cracking still. In such a still the pressure may similarly be varied and pressures of, for example, 90 to 125 lbs. employed or much higher pressures, for example, around 600 or 700 lbs. employed.

It will thus be seen that the present invention is of more or less general application for the utilization of hydrocarbon gases, either with or without admixture with liquefiable vapors, from pressure stills or other sources and enables such gases, or gases and vapors, to be utilized in a particularly advantageous manner. Where condensable vapors are present admixed with the gases, these vapors will be set free in the pressure still and will be recovered with the pressure distillate, although further reaction may take place between them or certain of their constituents such as unsaturated constituents, and other liquid or vapor constituents present in the pressure still. The present invention accordingly provides an improved method of absorption and recovery of such condensable vapors, while at the same time introducing permanent gases into the pressure still along with the charging oil therefor.

I claim:

1. The method of cracking heavier hydrocarbons to form lighter hydrocarbons which comprises subjecting a body of the heavier hydrocarbons to a cracking temperature under pressure, separating permanent gases from condensable vapors resulting from the cracking operation and collecting the hydrocarbon gases at a lower pressure, recompressing such gases and forcing the gases under pressure into relatively cool hydrocarbon oil and introducing the resulting oil, containing the absorbed and entrained gases, into the said body of oil maintained at a cracking temperature.

2. The method of cracking heavier hydrocarbons to form lighter hydrocarbons which comprises subjecting a body of the heavier hydrocarbons to a cracking temperature under pressure, separating permanent gases from condensable vapors resulting from the cracking operation by condensing the latter

and collecting the hydrocarbon gases at a lower pressure, recompressing such gases and forcing substantially all of them under pressure into relatively cool hydrocarbon oil and 5 introducing the resulting oil, containing the absorbed and entrained gases into the said body of oil maintained at a cracking temperature.

3. The method of cracking heavier hydrocarbons to form lighter hydrocarbons which 10 comprises subjecting a body of the heavier hydrocarbons to a cracking temperature under pressure, condensing the resulting vapors and separating the permanent gases therefrom at a lower pressure, compressing the separated gases and injecting gases containing constituents separated from the cracked vapors into cool oil under pressure and introducing the cool oil with absorbed constituents 15 contained therein directly into the body of oil maintained at the cracking temperature.

4. The method of cracking heavier hydrocarbons to form lighter hydrocarbons which 20 comprises subjecting a body of heavier hydrocarbons to a cracking temperature under pressure, withdrawing permanent gases and vapors generated and separating permanent gases from the readily condensable constituents 25 at a lower pressure, compressing gases containing constituents separated from the cracked vapors and injecting the gases so compressed into a body of relatively cool hydrocarbon oil under pressure, introducing oil 30 from the last named body together with gaseous constituents absorbed therein and admixed therewith directly into the body of oil 35 maintained at the cracking temperature.

5. The method of cracking heavier hydrocarbons to form lighter hydrocarbons which 40 comprises subjecting a body of the heavier hydrocarbons to a cracking temperature under pressure, withdrawing permanent gases and vapors generated and separating gases 45 from readily condensable constituents of the gas and vapor mixture at a lower pressure, compressing gases containing constituents separated from the cracked vapors and injecting the gases so compressed into a body of relatively cool hydrocarbon oil maintained 50 under pressure at least as high as the pressure maintained on the body of oil at the cracking temperature, introducing oil from the last named body together with gaseous constituents introduced thereinto directly into the 55 body of oil maintained at the cracking temperature.

In testimony whereof I affix my signature.
ROBERT J. BLACK.
